UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE:

1,309,423.

Specification of Letters Patent.

Patented July 8, 1919.

Application filed October 5, 1918. Serial No. 256,955.

To all whom it may concern:

Be it known that I, GEORGE A. SEIB, citizen of the United States, and resident of Ilion, in the county of Herkimer and State 5 of New York, have invented certain new and useful Improvements in Type-Writing Machines, of which the following is a specification.

My present invention relates to ribbon 10 mechanism for typewriting machines, and a principal object is to provide devices for automatically controlling the ribbon reversing device or weight when the associate ribbon spool is removed from and replaced on 15 its shaft or support. My invention is an improvement on the construction disclosed in the application of T. I. Fort, Serial No. 256,387 filed October 1, 1918.

To the above and other ends which will 20 hereinafter appear, my present invention consists in the features of construction, combinations of devices and arrangements of parts to be hereinafter described and particularly pointed out in the claims.

25 In the accompanying drawings,

Figure 1 is a fragmentary plan view, partly in section, illustrating the ribbon feeding and reversing mechanism of a Remington No. 10 typewriting machine to which 30 I have shown the preferred form of my invention as applied.

Fig. 2 is a sectional view taken axially through one of the ribbon spools and the shaft on which it is supported, illustrating 35 my invention associated therewith.

Fig. 3 is a fragmentary plan view, partly in section, of said ribbon spool, its shaft and associate parts.

40 Fig. 4 is a perspective view of my novel latching device.

Fig. 5 is a sectional view taken axially through the ribbon spool and its supporting shaft, and showing the relationship of the parts when the ribbon is entirely unwound 45 from said spool.

Fig. 6 is a side view of the ribbon spool shaft and associate parts, the parts being shown as they are related when the ribbon spool has been removed.

50 Fig. 7 is a view corresponding to Fig. 6 but showing the parts as they appear during the operation of replacing the ribbon spool on its shaft.

Fig. 8 is an end view, on an enlarged 55 scale, of the parts shown in Fig. 6.

Figs. 9 and 10 are opposite face views of the ribbon spool.

Referring first to Fig. 1, the carriage (not shown) is connected to its spring drum 1 by a strap 2. During leftward movements 60 of the carriage the spring drum turns a bevel gear wheel 3 which intermeshes with a corresponding bevel gear wheel 4 that is mounted on a ribbon driving shaft 5 in such a way that the shaft is always caused to 65 turn by the gear wheel 4 but may slide end- wise back and forth independently of said gear wheel. Fixed to said shaft near opposite ends are beveled pinions 6 and outside of said pinions the shaft is provided 70 with worms 7. The pinions 6 are adapted to mesh alternately with beveled gear wheels 8 that are fixed to the rear ends of horizontal spool shafts 9. Said shafts 9 bear in stationary lugs 10 and extend toward the 75 front of the machine, carrying at their forward ends ribbon spools 11, each ribbon spool comprising front and rear flanges 12 and 13 and a hollow core 14 having an opening or slot indicated at 15, the rear flange 80 13 being cut out as indicated at 16 in register with said opening (Figs. 2, 5 and 9). A ribbon 17 is wound on the spools, the free portion of said ribbon being threaded through a ribbon carrier or vibrator, not 85 shown, which is adapted to be vibrated at the type strokes in the way common to the No. 10 Remington typewriting machine, or in any other suitable manner.

Ribbon reversing mechanism is provided 90 by which the shaft 5 may be moved longitudinally back and forth so as to cause the driving pinions 6 to mesh in alternation with their associate gear wheels 8 and thus automatically feed the ribbon back and 95 forth between the spools. Said reversing mechanism comprises for each ribbon spool a rod 18 which is slidably mounted inside the associate ribbon spool shaft, said rod being passed through a slot 19 in said shaft, 100 the slot stopping short of the rear end of the shaft, leaving the rear portion 19^a, which is perforated as indicated at 19^b, so that near said rear end the rod 18 has a complete bearing opening, 19^b, in the shaft. The front 105 end of the reversing rod 18 is provided with an outwardly extending angular finger 20 that engages in an opening 21 in a weight device 22 that comprises a weight proper 23 and an angular shank or stem 24 to which 110

the weight is fixed. The weight, which is beveled at its end is normally housed within the hollow core 14 of the associate ribbon spool and is adapted to play in the opening 15 and the cut-out 16. The rear end portion of the stem 24 is angularly disposed and is bifurcated providing curved branches 25 to embrace loosely the shaft 9. The branched portions 25 are curled, as indicated at 26, to bear on pins 27 that project outward from opposite sides of a collar 28 that is secured by a screw 29 to the shaft. The weight 23 is normally retained within the core 14 by the coils of the ribbon 17 but when the ribbon is completely unwound from the spool the weight will be free to swing out under the influence of gravity to the position shown in Fig. 5. This movement of the weight operates through the finger 20 to slide the rod 18 rearward, causing its rear reduced end to project outward from its bearing and into engagement with the associate worm 7. After such engagement a slight further turning of the shaft 5 will cause it to be wormed or moved longitudinally so as to disengage the engaged driving pinion 6 from its gear 8. Devices not shown assist the completion of the longitudinal movement of the shaft to cause the other driving pinion 6 to engage with its gear wheel 8. The result is that one of the ribbon spools is disconnected from the ribbon driving shaft or source of power and the other ribbon spool is connected therewith so that the direction of longitudinal feed of the ribbon will be reversed.

It will be understood of course that in order to effect a reversal of the ribbon feed and wind the ribbon on and off the spools, each spool is provided with a train of automatic reversing devices such as has been described in order to project and withdraw the rods 18 into and from coöperation with their associate worms 7 so as to shift the driving shaft 5 longitudinally back and forth. The manner in which the rod 18 is projected when its associate weight 23 is released by the unwinding of the ribbon from the spool has been described, and it will be understood the projected rod will be drawn back within its bearing as the ribbon starts to rewind on the bared spool. Its first fold or ply passing over the dropped weight 23 will force said weight back within the core of the spool, this backward swinging of the weight acting through the finger 20 to withdraw or return the rod 18. The weight, in other words, acts through gravity and is prevented from dropping out of the spool by the ribbon; said weight normally resting on the plies of the ribbon which bridge the gap 15 in the core.

The ribbon spools are detachably supported on their shafts 9, the left-hand spool 65 being held in place in the present instance

by a screw 9^a and the right-hand spool by latching devices as is usual in the Remington machine. The spools when in place are forced to turn with their shafts by locking or engaging devices which will be briefly described. As clearly appears from Figs. 9 and 10, the flanges 12 and 13 of the ribbon spools are centrally perforated, as indicated respectively at 30 and 31, in order properly to fit over the shafts 9. The perforation 31 in the rear flange 13 is a round hole but the opening 30 in the forward flange 12 is provided with diametrically disposed inwardly projecting locking lugs 32. One of these lugs is adapted to fit between the walls at 80 the forward end of the slot-way 19 while the opposite lug is adapted to engage with a notch 33 cut in the forward end of the shaft 9 (Figs. 2 and 5), the construction being such that when the ribbon spool is in place 85 it will be forced to turn with its shaft. Latching devices may be employed for each spool to insure the retention of the spool on its shaft, but in the present instance are used only in connection with the right-hand 90 spool. Said devices comprise, as best shown in Figs. 2, 3 and 5, a latch proper 34 which is arranged within the slot 19 at the forward end of the shaft 9 and is pivoted on a pin 35 which bridges said slot. One arm of the 95 latch 34 is provided with a finger piece 36 which projects forward beyond the end of the shaft and the face of the ribbon spool, while its rear arm is provided with a locking nose 37 which coöperates with the inner 100 wall of the flange 13. This locking nose is normally controlled by a coiled spring 38 which is arranged within the slot 19 and confined between the latch 34 and the bottom wall of said slot. This spring tends constantly to press the nose 37 of the latch outward into locking engagement, as shown in Fig. 5, wherein the latch is in effective or locking position. In order to unlatch the spool preliminary to withdrawal it is necessary to press on the finger piece 36 so as to overcome the spring and force the nose back into the slotway 105 110 115 120 125 130 is in place and the weight is sustained by the ribbon. If, however, it is necessary or desirable to remove an empty spool, or one on which there are only one or two plies of ribbon, conditions which result in the weight 23 occupying a position different from the normal position as the result of having swung down or away from the shaft either to the full extent of movement or part way, then when the spool is removed my invention provides for picking up or acting on the weight or reversing device automatically and restoring it to its normal position close to the spool shaft. These functions will be more clearly understood from the detailed description of my automatic latching devices which follows. Said devices are cheap and simple in construction comprising only two parts, one a coiled spring and the other a sheet metal piece, which parts may be readily applied to existing constructions without changing or altering the latter. The latch proper, indicated as a whole by the numeral 39, is shown detached in Fig. 4. Preferably it may be made of sheet metal and cut out and bent to the shape shown. It comprises a triangular body portion 40, and a portion 41 bent at right angles thereto. The portion 41 is provided at its sides with forwardly bent ears, lugs or contact devices 42 and is formed with a round hole 43 to fit loosely over the shaft 9. The body portion 40 is formed with a triangular hole or opening indicated at 44 which at the rear terminates in a narrow slotway, indicated at 45, and at the front extends down into a notch or cut-out, indicated at 46, formed in the portion 41, the hole 44 being continuous and including slot 45 and notch 46. This angular member or latch is arranged loosely on the forward end portion of the associate shaft 9 between and externally of the collar 28 and the nose 37 of the latch 34, the narrow slotted rear end being disposed between the bifurcations or branches 25, there being of course one latch 39 for each shaft 9. The slot 45 is engaged loosely by the finger 20, while the weight 23 or the portion of the stem to which it is immediately attached, is adapted to be housed or seated loosely within the notch 46 and the wider part of the slot 44, thus affording a comparatively close approach of the weight 23 to the shaft 9. Surrounding the shaft 9 and confined between the collar 28 and the part 41 is a coiled spring 47 which is the second part or piece of my novel weight controlling mechanism. This spring tends constantly to press the latch 39 forward along the shaft, and when the spool is in place thereon maintains the contact lugs 42 in contact with the flange 13 of the ribbon spool, as shown in Figs. 1 to 5. When the ribbon spool is removed the spring 47 forces the loosely hung latch still farther forward until it is arrested by the engagement of the part 41 with the nose 37. This represents the extreme limit of forward movement of the latch and at this time the rear end of the slot 45 in the slotted shank portion of the latch is engaged with the laterally extending finger 20, and through the force of the spring 47 is holding said finger pressed forward, causing it, through its action on the weight 23, to hold said weight close to the shaft 9, as shown in said Fig. 6. In other words, at this stage, or when the ribbon spool is off, the latch 39 is effective to hold the weight 23 substantially in its normal position close to the ribbon spool shaft. Suppose now the operator starts to put the ribbon spool on the shaft, as illustrated in Fig. 7, the weight, being held up automatically by the spring latch 39, will pass readily into the opening 16 above the ribbon plies. As thereafter the spool is pushed farther back the flange 13, contacting with the lugs 42, will force the latch 39 rearward on the shaft 9, overcoming the spring 47 and freeing the finger 20 from the control of said latch, so that when the spool has been pushed back into place and latched, the finger will be entirely free so that the weight 23 will be completely restored to the control of the ribbon alone, the latch 39 being held in ineffective position, as shown in Figs. 1 to 5, by the ribbon spool itself. When, however, the ribbon spool is removed the spring 47 will again force the latch forward so that it will resume control of the weight 23 and hold it up through the action of the rear end of the slot 45 on the finger 20. My invention is preferably applied to both ribbon spool shafts.

It will thus be seen that I have provided a simple, inexpensive and effective controlling means for the ribbon reversing weight which relieves the operator of manipulating the weight by hand when putting the ribbon spools on their shafts. The stamped sheet metal latch device comprising a perforated bearing plate or part and an off-set slotted shank or member spaced away from the spool shaft on which the bearing plate is mounted and also being exterior or outside of the spring which presses it, is readily applied to the machine without necessitating changes in the latter.

Various changes may be made without departing from my invention.

What I claim as new and desire to secure by Letters Patent, is:

1. In a typewriting machine, the combination of a ribbon carrier, a shaft on which said carrier is detachably mounted, reversing mechanism including a device controlled by said carrier, and means for preventing said reversing device from affecting said reversing mechanism when the ribbon carrier is detached, said means comprising a stamped sheet metal piece mounted on

said shaft and a spring operative on said piece.

2. In a typewriting machine, the combination of a ribbon carrier; a shaft on which said carrier is detachably mounted; reversing mechanism including a weight and a collar fixed on said shaft and to which said weight is pivotally connected; and means for preventing said weight from affecting said reversing mechanism when the ribbon carrier is detached, said means comprising an angular plate mounted externally of said collar and a spring effective on said plate.

3. In a typewriting machine, the combination of a ribbon carrier; a shaft on which said carrier is detachably mounted; reversing mechanism comprising a weight connected to a bifurcated stem, and a collar fixed to said shaft and partly embraced by the bifurcations of said stem, said stem being pivoted to said collar; and means for preventing said weight from affecting said reversing mechanism when the ribbon carrier is detached, said means comprising a plate slidably mounted on said shaft and having a slotted portion extending externally of said collar between said bifurcations.

4. In a typewriting machine, the combination of a ribbon carrier; a shaft on which said carrier is detachably mounted; reversing mechanism comprising a weight connected to a bifurcated stem, a collar fixed to said shaft and partly embraced by the bifurcations of said stem, said stem being pivoted to said collar, and a reversing rod having a loose connection with said stem; and means for preventing said weight from affecting said reversing mechanism when the ribbon carrier is detached, said means comprising a plate slidably mounted on said shaft and having a slotted portion extending externally of said collar between said bifurcations, said slotted portion coöperating with a part of said rod, the slot in said plate having an extended portion adapted to accommodate said weight.

5. In a ribbon reversing mechanism, the combination of a spool shaft; a spring actuated latch connected to the reversing devices and slidably supported on the shaft and comprising a bearing portion and an offset slotted shank; a spool on said shaft against which said latch presses; and a catch for holding the spool in normal position and also for limiting the outward movement of the latch when the spool is detached.

6. In a ribbon reversing mechanism; the combination of a spool shaft; a spring actuated latch connected to the reversing devices

and slidably supported on the shaft and comprising a slotted shank, a bearing portion at right angles thereto, and forwardly extending projections; and a spool detachably connected to said shaft and against which said projections press when the spool is in working position.

7. In a ribbon reversing mechanism, the combination of a spool shaft, a reversing rod therein having a finger extending laterally outside the shaft, a spring pressed latch having a slotted shank spaced away from said shaft and that embraces said finger and having also a bearing portion 70 slidable on said shaft, a pivoted weight connected to said laterally extending finger, and a detachable spool mounted upon said shaft.

8. In a ribbon reversing mechanism, the combination of a spool shaft; a reversing rod therein having a finger extending laterally outside the shaft; a pivoted weight connected to said finger; a latch mounted on said shaft and comprising an off-set shank 80 extending parallel with said shaft; a detachable spool; and a spring for pressing said latch against said spool.

9. In a ribbon reversing mechanism, the combination of a spool shaft; a reversing rod therein having a finger extending laterally outside the shaft; a pivoted weight connected to said finger; a sheet metal latch mounted on said shaft and comprising a perforated bearing plate and an off-set slotted shank extending parallel with said 90 shaft; a detachable spool; and a spring for pressing said latch against said spool.

10. In a ribbon reversing mechanism or the character described, a sheet metal spring pressed weight holding latch consisting of a 100 slotted shank, a bearing portion, and projections or ears extending forwardly from the latch.

11. In a ribbon reversing mechanism, the combination of a spool shaft, a reversing 105 weight supported thereon, a sliding pin to which said weight is connected, a coiled spring on said shaft, a latch slidably supported on said shaft and having a member external to said shaft and to said spring 110 operatively connected to said sliding pin, and a detachable spool on said shaft.

Signed at Ilion, in the county of Herkimer, and State of New York this 30th day of September A. D. 1918.

GEORGE A. SEIB.
